UNITED STATES PATENT OFFICE.

CHARLES E. CHAPIN, OF GREENWICH, AND WALTER E. PATCHIN, OF BRIDGEPORT, CONNECTICUT; SAID PATCHIN ASSIGNOR TO SAID CHAPIN.

CARBON-FEEDING DEVICE.

SPECIFICATION forming part of Letters Patent No. 693,495, dated February 18, 1902.

Application filed May 4, 1901. Serial No. 58,712. (No model.)

To all whom it may concern:

Be it known that we, CHARLES E. CHAPIN, residing at Greenwich, and WALTER E. PATCHIN, residing at Bridgeport, Connecticut, citizens of the United States, have invented certain new and useful Improvements in Carbon-Feeding Devices, of which the following is a clear, full, and exact description.

Our invention relates to a feeding device for a carbon in an arc-lamp; and our object is to provide a device which will be simple and positive in its action and which will feed the carbon steadily and smoothly. Other advantages will be apparent from the following description and accompanying drawings, which show the preferred embodiment of our invention, and the invention will be defined in the claims.

In the drawings, Figure 1 shows a side elevation of our device, parts being in section. Fig. 2 is a diagram showing the electric connections, and Figs. 3 and 4 show details.

In many of the feeding devices of the prior art the carbon is not fed smoothly or steadily. The clutching devices are not accurate in their operation and the rod often binds in the guideway, particularly if it is slightly too large, and the arc is consequently irregular. It has been our object to obtain a device which will avoid these objections, and in the present embodiment we have provided a roller and means to automatically move the roller away from the rod to release the latter and allow it to move when the arc is broken and toward said rod to hold the same when the circuit is closed.

In the preferred embodiment of our invention shown in the drawings, A is the floor of the lamp, having an opening therein through which passes the carbon-rod B. By "carbon-rod" or "rod" we mean to include both the carbon itself and a rod to which the carbon may be attached, and we do not intend by either of those expressions to limit ourselves to the use of either alone or to both together, as by our invention we can feed the bare carbon or a rod to which the carbon itself may be attached with substantially equal ease.

C is a roller, preferably concave, as shown in Fig. 4, which is movable laterally of rod B to hold or release the rod. We preferably also have a second concave roller D. These

two rollers hold rod B between them, and thus form a guideway for the rod. The roller C is preferably carried by an arm E, pivoted to a roller-frame F. Roller D is preferably pivoted so that it is not movable laterally of the rod.

In order to move the roller C into engagement with rod B, we have in this embodiment provided a lever G, which may be pivoted at 60 *g* to a part of the frame and weighted, so that it will normally drop to the position shown in full lines in Fig. 1, and a connection between the lever and arm E, including a link H, pivoted to arm E and to a head I. In order to 65 adjust the parts, we may have a screw-threaded end *i*, passing through the light end of lever G, upon which turns a thumb-nut K.

The carbon-rod B preferably moves downward toward the substantially stationary 70 lower carbon under the influence of gravity acting on the rod itself when released, as is common in such devices, and in order to move the roller C away from the rod to release the same we have in the embodiment shown provided a solenoid S in a shunt of comparatively 75 high resistance around the arc, as seen in Fig. 2, so that when the arc-circuit is opened—for instance, by the breaking of the arc by the too great separation of the carbon points—80 the solenoid will be energized and will draw upward its core T, carried on the end of lever G, thus throwing the parts into the dotted position in Fig. 1 and releasing the rod B.

We preferably make the rollers C and D 85 also movable longitudinally of rod B. In the present embodiment the roller-frame F is not fixed with relation to the floor A of the lamp, but tends to drop down on the same. When the lever G is drawn upward by the solenoid 90 into the dotted position, the frame F will drop down onto the floor A, and when the arc-circuit is closed the solenoid will be deenergized and the lever G will drop, thus rocking arm E, and the rod B will be grasped and held between rollers C and D, and a further movement of lever G to its normal position will raise frame F and the rod B bodily upward 95 together to the position shown in Fig. 1, thus separating the carbon points and allowing 100 the arc to form. The amount of separation may be controlled by thumb-nut K.

Our device is simple and efficient and feeds the carbon smoothly and steadily, whether rod B is the carbon itself or not, and the rod can freely pass through without binding, even 5 if it is larger than the normal size, and it will be securely held even if of a smaller size.

It will be obvious and we are aware that many changes may be made in the embodiment illustrated and described without departing from our invention, and we therefore do not desire to be limited to the construction herein disclosed.

What we claim is—

1. In a carbon-feeding device in combination, a carbon-rod movable downward by gravity, a guideway for the same including a plurality of rollers adapted to hold said rod between them and being movable longitudinally of the same, one of said rollers being 15 carried on a pivoted elbow-lever whereby the same is movable laterally of said rod to release the same when the arc-circuit is opened, an overweighted lever connected to said arm and adapted to fall by its own weight and 20 move said roller into engagement with said rod to hold and also raise the same, and an electromagnet in a shunt around the arc adapted to raise said lever when the arc-circuit is opened and move said roller away from 25 said rod to release said rod and allow the same to fall.

2. In an arc-lamp carbon-feeding device in combination a carbon-rod, a holder for the same through which said rod passes loosely, 35 said holder being movable up and down with said rod, an elbow-lever pivoted to said holder and carrying a roller pivoted on one of its arms, an overweighted pivoted lever connected with the other arm of said elbow-lever 40 and adapted to fall by its own weight and cause said roller to clutch said rod and raise said holder and rod, and an electromagnet in shunt around the arc and adapted to raise said weighted lever and release said clutch 45 when said arc is broken.

3. In an arc-lamp carbon-feeding device in combination a carbon-rod, a holder for the same through which said rod passes loosely, said holder being movable up and down with

said rod, an elbow-lever pivoted to said holder 50 and having an upwardly-projecting arm, a roller pivoted on said arm, an overweighted pivoted lever connected with the other arm of said elbow-lever and adapted to fall by its own weight and rock said elbow-lever and 55 thereby cause said roller to clutch said rod and raise said holder and rod, and an electromagnet in shunt around the arc and adapted to raise said weighted lever and release said clutch when said arc is broken. 60

4. In an arc-lamp carbon-feeding device in combination a carbon-rod, a holder for the same through which said rod passes loosely, said holder being movable up and down with said rod, an elbow-lever pivoted to said holder 65 and having an upwardly-projecting arm carrying a roller pivoted thereon, a stationary roller also carried on said holder, said rod being located between said two rollers, an overweighted pivoted lever connected with the 70 other arm of said elbow-lever and adapted to fall by its own weight and cause said roller to clutch said rod between said two rollers and raise said holder and rod, and an electromagnet in shunt around the arc and adapted 75 to raise said weighted lever and release said clutch when said arc is broken.

5. In an arc-lamp carbon-feeding device in combination a carbon-rod, a holder for the same through which said rod passes loosely, 80 said holder being movable up and down with said rod, a lever pivoted to said holder and carrying a roller, an overweighted pivoted lever connected with one arm of said first lever by a longitudinally-adjustable connection and adapted to fall by its own weight and cause said holder to clutch said rod and raise said holder and rod, and an electromagnet in shunt around the arc and adapted to 85 raise said weighted lever and release said clutch when said arc is broken. 90

Signed at Bridgeport, Connecticut, this 3d day of January, 1901.

CHARLES E. CHAPIN.
